UNITED STATES PATENT OFFICE

110,288

DESIGN FOR AN ELECTRIC FENCE CONTROLLER PANEL

Sidney A. Moore, Milwaukee, Wis., assignor to
The Prime Manufacturing Company, Milwaukee,
Wis., a corporation of Wisconsin

Application February 11, 1938, Serial No. 75,072

Term of patent 7 years

To all whom it may concern:

Be it known, that I, Sidney A. Moore, a citizen of the United States, residing at Milwaukee, in the county of Milwaukee and State of Wisconsin, have invented a new, original, and ornamental design for an Electric Fence Controller Panel, of which the following is a specification, reference being had to the accompanying drawing, forming part thereof.

Figure 1 is a front plan view of an electric fence controller panel embodying my new design; and

Figure 2 is a side view thereof.

I claim:

The ornamental design for an electric fence controller panel, as shown.

SIDNEY A. MOORE.
